CLAIM

The ornamental design for a cover for a camera, as shown and described.

DESCRIPTION

FIG. 1 is a front view of a cover for a camera according to my new design;

FIG. 2 is a back view thereof;

FIG. 3 is a left-side view thereof;

FIG. 4 is a right-side view thereof;

FIG. 5 is a top view thereof;

FIG. 6 is a bottom view thereof; and,

FIG. 7 is a perspective view thereof.

The broken lines depict portions of the cover for a camera in which the design is embodied that form no part of the claimed design.

1 Claim, 7 Drawing Sheets
